APPARATUS FOR FORMING METAL PARTS

Original Filed April 9, 1937

UNITED STATES PATENT OFFICE

2,240,294

APPARATUS FOR FORMING METAL PARTS

Edward J. Greif, Chicago, Ill., assignor to Borg-Warner Corporation, Chicago, Ill., a corporation of Illinois

Original application April 9, 1937, Serial No. 135,990. Divided and this application November 30, 1938, Serial No. 243,169

12 Claims. (Cl. 153—21)

This invention relates to the making of large volume receptacles such as washing machine tubs, and has as its primary object to provide apparatus for forming in a washing machine tub of the type wherein the side wall of the tub is connected to a mouth of reduced diameter by an upwardly and inwardly curving integral shoulder region, a sunken, concealed cover seat in which the cover may be supported with its edges concealed and its upper surface forming a smooth symmetrical continuation of said curved shoulder region. The present application is a division of my pending application Serial No. 135,990, filed April 9, 1937, for "Forming metal parts."

The apparatus of the present invention forms one of a series of mechanisms for performing a series of operations upon the receptacle. In one of the intermediate operations, the neck region is folded axially into the receptacle from the rim of the in-curved shoulder region. The apparatus of the present invention operates upon the substantially cylindrical neck region thus formed, so as to form the cover seat therein by the action of opposed axially movable die elements. The invention deals with the problem of applying a forming die to the peripheral surface of the in-folded neck region, which forming die must be necessarily of greater diameter than the diameter of the mouth of the receptacle and yet must be inserted through said mouth in order to gain access to said peripheral surface. This problem is met by providing a die element in the form of a sectional annulus, the sections of which may be separately inserted and removed.

The object of the invention, therefore, is to provide an apparatus including such a sectional die, adapted to cooperate with a complementary male die element for forming the cover seat in the in-folded neck region when the die elements are urged axially toward each other under pressure, together with means insertable through the receptacle mouth and adapted to be extended radially into engagement with the annular die element and to transmit axial pressure thereto.

Other objects of the invention are to provide means for supporting the curved shoulder region of the receptacle against deformation during the forming of the neck region, for stripping the receptacle from the die at the completion of the forming operation, and for retracting the pressure applying means to a position allowing the removal of the receptacle.

The above and other objects, advantages and uses of my invention will become apparent from a reading of the following specification and claims

taken in connection with the appended drawing which forms a part of the specification and wherein:

5 Fig. 1 is an axial sectional view through a portion of an apparatus embodying the invention, the parts being shown in the position of completion of the forming operation;

Fig. 2 is a plan view of a portion of such apparatus; and

10 Fig. 3 is an axial sectional view of a portion of such apparatus, the parts being shown in an initial stage of operation.

In the process of fabricating a washing machine tub, one step of which is performed by the apparatus of the present invention, a sheet metal blank is first drawn into the general shape of the tub, having a bottom wall 10 provided with a central aperture 11 for reception of the agitator drive shaft, and having a side wall 12. The edge region of the side wall 12 is, in a subsequent operation, curved inwardly to form the shoulder portion 13 and a neck region which projects radially inwardly of the shoulder 13. This neck region is, in a subsequent operation, folded axially into the receptacle to form a substantially cylindrical neck region 14 shown in Fig. 3, spaced from the side wall 12 by an annular space 15. The rim 16 of the tub is formed by the junction between the neck region 14 and the shoulder 13.

15 30 That portion of the neck region 14 which lies adjacent the rim 16 is cylindrical, as at 18, and the remainder thereof is frusto-conical, converging toward the bottom of the tub. The method and apparatus for bringing the tub to this stage of formation is illustrated and described in the aforesaid co-pending application Serial No. 135,990.

35 The present invention provides apparatus for 40 die forming the neck region 14 so as to produce therein a seat 17, connected to the rim 16 by the throat 18, and terminating in an inwardly off-set flange 19, which is, in a subsequent and final operation, curled radially outwardly so as to remove the edge region thereof from the region of probable contact with clothes being inserted into and withdrawn from the tub.

45 The apparatus of the present invention includes a supporting ring 20 for supporting the tub in an inverted position during the seat forming operation, a male die element 21 adapted to engage the inner surface of the neck region 14, an annular die element 22 receivable in the annular space 15 and adapted to cooperate with the male die element 21 in forming the seat 17, and means,

indicated generally at 23, for applying downward pressure to the annular die element 22.

The supporting ring 20 includes an upstanding annular flange 24 for receiving the side wall 12 of the tub, and a downwardly and inwardly curving seat 25 adapted to conform to the surface of the shoulder 13 so as to preserve the shape thereof during the seat forming operation.

In order that the tub may be freely inserted into the supporting ring 20 in preparation for the forming operation, the ring 20 is constructed so that it may expand to a normal, unstressed position wherein the internal diameter of the flange 24 is substantially greater than that of the side wall 12 of the tub, as indicated in Fig. 3. From this normal position, it is adapted to contract into snug constricting engagement with the tub as shown in Fig. 1. This contraction is effected automatically during the forming operation as a result of downward movement of the ring 20 from the initial position shown in Fig. 3 to a position contacting the upper surface 26 of a base 27 on which the several parts are supported. In thus moving downwardly, a frustoconical outer surface 28 of the ring 20 cooperates with the conforming inner surface 29 of an upstanding flange 30 formed integrally with the base 27 at the periphery thereof, resulting in the forced contraction of the supporting ring 20 against the resistance of its inherent expanding force. The ring 20 is split so as to allow the required amount of expansion and contraction.

The annular die element 22 is in the form of circumferentially severed sections adapted to be inserted one by one into the annular space 15 prior to the positioning of the tub between the ring 20 and male die element 21. The die elements 21 and 22 are provided with cooperating forming surfaces having the shape of the finished seat 17 and the adjacent regions 18 and 19 of the neck region.

The male die element 21 is fixedly positioned upon the base 27, and the annular die element 22 is adapted to move downwardly in order to effect the forming operation.

The die element 22 has a rounded corner 31, which, together with the conical form of the neck region 14, allows the die elements to slide smoothly over and into the neck region 14 with a purely axial movement so as to form the two regions of different diameter separated by an offset, without buckling the neck region.

The means for forcing the annular die element 22 downwardly comprises a plurality of radial jaws 32 pivoted at 33 upon brackets 34 which are secured to the male die element 21 by means of bolts 35. The jaws 32 are adapted to swing radially outwardly and downwardly, and are thus adapted to assume an initial position, shown in dotted lines in Fig. 1, lying wholly within the innermost circumference of the mouth of the tub so that they may freely enter the mouth as the tub is placed in position in the die mechanism. From this initial position, the outward and downward swinging serves first to extend the jaw members radially until they project above the annular die element, and, in the latter stage of such movement, to apply downward pressure to the annular die element.

The jaws 32 are spaced apart circumferentially just sufficiently to accommodate the lifting rods 33 which project vertically between them. Upon the lower ends of the rods 33 are threaded nuts 34 which engage the lower edges of the jaws 32 for applying lifting pressure thereto. The upper

regions of the lifting rods 33 are slidably mounted in a pressure plate 36 and provided with heads 37 adapted to be engaged by said plate 36 for lifting the jaws 32 to their starting positions 5 during the return stroke of the press in which the mechanism is mounted.

The pressure plate 36 is mounted upon a plunger 38 and abuts a shoulder 39 thereof from which it receives downward pressure on the downward stroke thereof. The reduced lower end 40 of the plunger 38 is slidably mounted in a bearing 41, mounted in an aperture 42 in the base 27.

Guide posts 43 are slidably extended at 44 through the pressure plate 36 and threaded into the male die element 21 as shown. Encircling the posts 43 are compression springs 45 which are compressed during the downward stroke of the pressure plate, and which, upon the return stroke of the plunger 38, force the pressure plate 36 back upwardly to its starting position shown in dotted lines. The upward movement of the pressure plate is limited at this position by heads 46 on the posts 43.

In the operation of the apparatus, the tub is inverted and placed over the pressure transmitting apparatus 23 while the latter is in its retracted position shown in dotted lines, the post 38 at the time being elevated to a height sufficient to allow the tub to be inserted beneath its lower end. The rim region of the tub is fitted into the space between the supporting ring 20 and the male die element 21. Prior to placing the tub in position in the die apparatus, the sectional annular die 22 has been inserted in the annular space 15 within the tub, as previously described.

The tub being properly positioned in the die apparatus, the plunger 38 is lowered through the opening 11 in the tub until the shoulder 39 contacts the pressure plate 36. The parts are then in the position shown in Fig. 3, the supporting ring 20 being in its raised and expanded position, the shoulder 13 of the tub resting against the seat 25 thereof, and the annular die element 22 resting against the upper edge of the neck region 14.

Continued downward movement of the plunger 38 under pressure given to it by suitable cross mechanism, causes the jaws 32 to swing outwardly and then downwardly into engagement with the annular die element 22. From this point the jaws 32 commence to apply downward pressure to the annular die element.

This downward pressure causes the annular die element 22 to be forced downwardly into the annular space 15 until its curved lower surface 47 contacts the inner surface of the shoulder region 13, pinching the shoulder against the curved die surface 25 of the supporting ring 20. From this point, the ring 20 will be forced downwardly and inwardly and the die elements 21 and 22 will commence the forming operation. At the completion of the stroke, the ring 20 will be fully contracted and the seat 17 will be fully formed. Since the shoulder 13 is tightly engaged between the annular die element 22 and the supporting ring 20 during the forming operation, its smoothly curved shape will be fully preserved without any buckling or wrinkling therein.

Upward movement of the post 38 allows the pressure plate 36 to be returned to its starting position by the retractor springs 45, and near the top of the stroke, the ring 20 is raised by means of chains 48, thereby releasing its constricting

engagement of the tub, and stripping the tub upwardly from the die element 21. The plunger 38 is then removed through the opening 11, and the tub is removed from the die apparatus. Lastly, the sections of the annular die element 22 are removed from the tub by inserting a suitable tool, provided for that purpose, into a groove 49 in the annular die element.

I claim:

1. Apparatus for forming a cover seat in a mouth-defining neck region of a receptacle wherein said neck region projects axially into the receptacle in spaced relation to the side wall thereof from an in-turned rim; comprising a male die element adapted to engage the inner surface of said neck region, an annular die element insertible into the receptacle through the mouth thereof and receivable in the annular space between said neck region and the side wall, and means insertible into the receptacle through the mouth thereof and adapted to apply pressure to said annular die element for moving the same toward said male die element whereby to form said neck region between said die elements.

2. Apparatus for forming a cover seat in a mouth-defining neck region of a receptacle wherein said neck region projects axially into the receptacle in spaced relation to the side wall thereof from an in-turned rim; comprising a male die element adapted to engage the inner surface of said neck region, a sectional annular die element adapted to be inserted through the receptacle mouth and into the annular space between the neck region and the side wall, and means insertible through the receptacle mouth and engageable with said annular die element for applying pressure thereto whereby to form said neck region between said die elements.

3. Apparatus for forming a cover seat in a mouth-defining neck region of a receptacle wherein said neck region projects axially into the receptacle in spaced relation to the side wall thereof from an in-turned rim; comprising a male die element adapted to engage the inner surface of said neck region, a sectional annular die element adapted to be inserted through the receptacle mouth and into the annular space between the neck region and the side wall, and means insertible through the receptacle mouth and radially extensible into engagement with said sectional die for moving the latter toward said male die element whereby to form said neck region between said die element.

4. Apparatus for forming a cover seat in a mouth-defining neck region of a receptacle wherein said neck region projects axially into the receptacle in spaced relation to the side wall thereof, from the rim of an in-curved shoulder region; comprising a die including an annular supporting ring shaped to conform to said shoulder and adapted to support the same against deformation during the forming operation and a male die element adapted to engage the inner surface of said neck region, a sectional annular die element adapted to be inserted in the annular space between the neck region and the side wall, and means adapted to apply pressure to said annular die element within the receptacle for moving said annular die element toward said male die element whereby to form said neck region between said die elements.

5. Apparatus for forming a cover seat in a mouth-defining neck region of a receptacle wherein said neck region projects axially into the receptacle in spaced relation to the side wall

thereof from an in-turned rim; comprising a downwardly yieldable contractile supporting ring adapted to receive the rim and adjacent wall region of the receptacle and to support the receptacle in an inverted position, means adapted to coat with said ring when the latter is moved downwardly for contracting the same into snug engagement with the receptacle, a male die element adapted to engage the inner surface of said neck region, an annular die element insertible in the annular space between the neck region and the side wall, and means insertible into the receptacle and engageable with said annular die element for applying downward pressure thereto whereby to force said supporting ring downwardly and form said neck region between said die elements.

6. Apparatus as defined in claim 5, including means to raise said supporting ring at the end of the forming operation so as to strip the receptacle from said male die element.

7. Apparatus for forming a cover seat in a mouth-defining neck region of a receptacle wherein said neck region projects axially into the receptacle in spaced relation to the side wall thereof, from the rim of an incurved shoulder region; comprising a fixed male die element adapted to engage the inner surface of said neck region, an axially yieldable ring interiorly shaped to conform to the surface of said shoulder region and adapted to receive the same in an initial position axially removed from said male die element, an annular die element insertible in the annular space between the neck region and the side wall of the receptacle, means for applying axial pressure to said annular die element so as to move the same toward said male die element, said annular die element being adapted to transmit said pressure through said shoulder region to said ring and to thereby move said ring axially, and means cooperating with said ring when thus moved axially for contracting the same into constricting engagement with said shoulder region for preserving the contour thereof during the forming operation.

8. Apparatus as defined in claim 7, wherein the means for contracting said ring comprises a base supporting said male die element and having an upstanding flange provided with an inner frusto-conical surface adapted to coat with a conforming surface on the periphery of said ring.

9. Apparatus for forming a cover seat in a mouth-defining neck region of a receptacle wherein said neck region projects axially into the receptacle in spaced relation to the side wall thereof from an in-turned rim; comprising a male die element adapted to engage the inner surface of said neck region, an annular die element receivable in the annular space between the neck region and the side wall, and a plurality of jaws pivoted at points located on a lesser radius than the minimum radius of the receptacle mouth and adapted to swing radially outwardly from positions wherein they are insertable through the receptacle mouth, to positions wherein they are engageable with said annular die element and adapted to transmit pressure thereto for moving the same toward said male die element whereby to form said neck region between said die elements.

10. Apparatus as defined in claim 9, including a pressure plate associated with said jaws and adapted to apply pressure thereto from a press plunger.

11. Apparatus as defined in claim 9, including

means for simultaneously engaging said jaws and transmitting pressure to them, and means operable upon the release of said jaw engaging means for retracting said jaws to positions wherein they may be removed from the receptacle.

12. Apparatus as defined in claim 9, wherein said jaws are pivoted to said male die element, and including a pressure plate adapted to engage said jaws for applying pressure thereto, retractor

springs between said pressure plate and said male die element for retracting said pressure plate when the pressure thereon is relieved, and retractor elements carried by said pressure plate and adapted to engage said jaws for retracting the jaws to positions wherein they may be removed from the receptacle.

EDWARD J. GREIF.
